LICENSE PLATE BRACKET FOR BICYCLES

Millard Morris, Denver, Colo., assignor to Leonard B. Lodmell and Delia B. Lodmell, both of Denver, Colo.

Application January 28, 1949, Serial No. 554

Term of patent 14 years

(Cl. D90—1)

To all whom it may concern:

Be it known that I, Millard Morris, a citizen of the United States, residing in the city and county of Denver and State of Colorado, have invented a new, original, and ornamental Design for a License Plate Bracket for Bicycles, of which the following is a specification, reference being had to the accompanying drawing, forming part thereof.

In the drawing:

Figure 1 is a side elevation of a license plate bracket for bicycles, showing my new design;

Figure 2 is a rear elevational view;

Figure 3 is a front elevational view drawn to an enlarged scale; and

Figure 4 is a section taken on line 4—4, Figure 3.

I claim:

The ornamental design for a license plate bracket for bicycles, as shown.

MILLARD MORRIS.
